(57) **CLAIM**

The ornamental design for the mosquito trapping device, as shown and described.

DESCRIPTION

FIG. 1 is a perspective view of a first embodiment of the mosquito trapping device of the present invention.

FIG. 2 is a front elevation view of the mosquito trapping device shown in FIG. 1.

FIG. 3 is a right side elevation view of the mosquito trapping device shown in FIG. 1.

FIG. 4 is a top plan view of the mosquito trapping device shown in FIG. 1.

FIG. 5 is a bottom plan view of the mosquito trapping device shown in FIG. 1.

FIG. 6 is a rear elevation view of the mosquito trapping device shown in FIG. 1.

FIG. 7 is a left side elevation view of the mosquito trapping device shown in FIG. 1.

FIG. 8 is an isometric view of a second embodiment of the mosquito trapping device showing a propane tank secured on the base.

FIG. 9 is a front elevation view of the mosquito trapping device shown in FIG. 8.

FIG. 10 is a right side elevation view of the mosquito trapping device shown in FIG. 8.

FIG. 11 is a top plan view of the mosquito trapping device shown in FIG. 8.

FIG. 12 is a bottom plan view of the mosquito trapping device shown in FIG. 8.

FIG. 13 is a rear elevation view of the mosquito trapping device shown in FIG. 8; and,

FIG. 14 is a left side elevation view of the mosquito trapping device shown in FIG. 8.
